CLAIM

The ornamental design for a chisel, as shown and described.

DESCRIPTION

FIG. 1 is a perspective view of a chisel embodying our new design, wherein the surfaces are shaded to show contour;

FIG. 2 is a front elevation view thereof;

FIG. 3 is a rear elevation view thereof;

FIG. 4 is a side elevation view thereof;

FIG. 5 is an opposing side elevation view thereof;

FIG. 6 is a top plan view thereof; and

FIG. 7 is a bottom plan view thereof.

FIG. 8 is a perspective view of the chisel in FIGS. 1-7, wherein the line shading is omitted for greater edge visibility;

FIG. 9 is a front elevation view thereof;

FIG. 10 is a rear elevation view thereof;

FIG. 11 is a side elevation view thereof;

FIG. 12 is an opposing side elevation view thereof;

FIG. 13 is a top plan view thereof; and,

FIG. 14 is a bottom plan view thereof.

The broken lines having equal segments represent portions of the article that form no part of the claimed design.

The broken lines having unequal segments represent a boundary of the claimed design and form no part of the claimed design.
